UNITED STATES PATENT OFFICE.

WILLIAM T. SEERUP, OF POCAHONTAS, ARKANSAS.

FOLDING ROCKING-CHAIR.

SPECIFICATION forming part of Letters Patent No. 697,025, dated April 8, 1902.

Application filed August 21, 1901. Serial No. 72,852. (No model.)

To all whom it may concern:

Be it known that I, WILLIAM T. SEERUP, a citizen of the United States, residing at Pocahontas, in the county of Randolph and State 5 of Arkansas, have invented certain new and useful Improvements in Folding Rocking-Chairs, of which the following is a specification.

This invention relates to certain new and 10 useful improvements in folding rocking-chairs; and the objects of the invention are to provide a chair of this character which shall be simple in construction, strong, inexpensive, and easy to fold up or unfold, as required, and which when in its folded condition will occupy comparatively little space for convenient transportation or storage.

To these ends the invention consists in the construction and arrangement of parts substantially as hereinafter set forth, and illustrated in the accompanying drawings, where- 15 in—

Figure 1 is a side elevation of a rocking-chair embodying my improvements. Fig. 2 20 is a vertical central section of the chair when folded up. Fig. 3 is a horizontal section on the line 3 3, Fig. 1; and Fig. 4 is a perspective view, on an enlarged scale, showing the adjustable hinge connection between the back 25 and the legs.

Referring now to the drawings, in which corresponding reference-letters denote like parts in the several views, A and B indicate the front and back legs, which cross each 30 other about midway between their ends and are pivotally connected together at the point of crossing by a rod or round a, extending at its ends through openings in the legs. As shown, the corresponding opposite legs are 35 connected and braced by rounds a' and b and cross-bars a², a³, and b', the bars a² and b' forming also supports for the attachment of a seat C, which may be made of any suitable 40 flexible material. The legs are supported on 45 rockers D D, each composed of two sections d d, arranged side by side and pivoted together near their inner ends by a pin e and connected near their outer ends to the lower ends of the legs by pivot-pins f f. Suitable 50 stops are employed to maintain the rocker-sections in proper relative position when the chair is in its unfolded condition. Thus, as

shown, each section d is provided with a laterally-extending stop-pin g and an edge notch h, so arranged that when the sections are in 55 the position indicated in Fig. 1 the pin on one section enters the notch of the other section, thereby securing the sections in line against independent upward movement and movement inwardly, while at the same time permitting them to be readily moved out of line in the opposite direction and folded outwardly, as required in folding the chair.

E E are arms, preferably upwardly arched and connected at their forward ends by pivot- 65 pins i i to the upper ends of the legs B B, while at their rear ends they extend between the cross-bars a² a³ of the legs A A. As preferred, these arms are curved in the direction of their length and terminate at the rear 70 in branches j j, the corresponding opposite branches being connected by rounds k k. When the parts are in the position shown in Fig. 1 and at the left, Fig. 3, the branches fit snugly between the cross-bars a² a³, and the 75 upper round k engages stop-pins l l, which extend downward from the bar a³ and tend to limit the movement of the arms in one direction, as will be understood.

F is a back consisting, as usual, of side bars 80 m m and cross-pieces n n firmly secured together. This back has a slidable hinge connection at its lower end with the upper ends of the legs A A, and means are employed to lock the back in its upright position substan- 85 tially in line with said legs or to permit it to swing backward in the act of folding the chair. Thus these legs are provided with slots o o, into which enter bolts p p, extending laterally from the side bars m m, and 90 nuts q q, screwing onto the bolts, serve to secure the parts loosely together, guard-plates r r, attached to the legs, forming bearings for the nuts.

Plates s s, secured to the outer faces of the 95 legs A, carry pins s' s', adapted to engage the adjacent edges of the arms m m of the back, while similar plates t t, attached to the inner faces of the arms, are provided with pins t' t' in position to enter behind upwardly-extend- 100 ing arms u u, formed in one piece with metal strap u' u', fastened to the legs, the strap preferably extending around the upper ends of the legs to strengthen them and protect

them against wear. It will thus be seen that when the back is upright and so adjusted that the bolts p p occupy the lower ends of the slots o o the pins s t lock the back against

5 forward or backward movement, while when the back is raised sufficiently to disengage the pins it may be freely swung on the bolts p p , as desired.

To fold up the chair, as shown in Fig. 2, 10 the back F is preferably first raised to unlock it in the manner already indicated, when the rocker-sections d d are swung downward out of line and the legs drawn together at their upper ends, after which the back is swung 15 backward over the upper ends of the legs B B and folded down to a position substantially parallel with the legs A A , the arms E E at the same time moving backward and downward between the cross-bars a^2 a^3 . To unfold 20 the chair ready for use, the operation is reversed.

It will be apparent from the foregoing that my improved chair may be easily and quickly folded up into compact form, or be readily 25 unfolded for use, and that it is composed of comparatively few parts, which are not liable to be broken or get out of order.

Without limiting myself to the exact construction shown and described, I claim—

30 1. In a folding chair, the combination with folding legs pivoted to each other, of outwardly-folding sectional supports for the legs, and means carried by the supports for maintaining the parts of the same in proper relative position when the chair is unfolded, substantially as described.

2. In a folding chair, the combination with folding legs pivoted to each other, of outwardly-folding sectional rockers connected to 40 the legs, and means carried by the rockers for maintaining the parts of the same in proper relative position when the chair is unfolded, substantially as described.

3. In a folding chair, the combination with 45 legs pivoted to each other, of outwardly-folding sectional rockers supporting the legs, and means carried by the rockers for maintaining the parts of the same in proper relative position when the chair is unfolded, substantially as described.

4. In a folding chair, the combination with 50 pivotally-connected legs, of outwardly-folding sectional rockers connected thereto, and means carried by the rockers for securing the sections against independent movement, substantially as described.

5. In a folding chair, the combination with pivotally-connected legs, of outwardly-folding rockers composed of pivoted sections connected to the legs, and means carried by said sections for securing the same against independent movement, substantially as described.

6. In a folding chair, the combination with 65 pivotally-connected legs, of outwardly-folding rockers composed of sections pivoted to

each other and to the legs, and means carried by said sections for securing the same against independent movement, substantially as described.

7. In a folding chair, the combination with pivotally-connected legs, of outwardly-folding rockers composed of sections pivoted to each other and to the legs, and means carried by the sections for preventing the movement of the same in an inward direction, substantially as described.

8. In a folding chair, the combination with pivotally-connected legs, of rockers connected thereto each composed of sections pivotally connected near their inner ends and stops carried by said sections for limiting the movement of the same in an inward direction, substantially as described.

9. In a folding chair, the combination with 85 pivoted folding legs, of rockers composed of sections pivoted to each other and to the legs, a back connected to the legs, and means for locking the back in an upright position, substantially as described.

10. In a folding chair, the combination with pivotally-connected legs, of rockers secured thereto composed of sections pivotally connected near their inner ends, and a stop-pin on each section adapted to enter a notch in 95 another section, to limit the inward movement only of the sections, substantially as set forth.

11. In a folding chair, the combination of 100 the front and back legs pivoted together between their ends, the rockers secured to the legs and each composed of two sections pivotally connected near their inner ends, a back hinged to the upper ends of the front legs, and means for locking the back in an upright 105 position, substantially as described.

12. In a folding chair, the combination of 110 the pivoted legs, the rockers therefor each composed of two sections pivoted together near their inner ends, and a stop-pin on each 115 section adapted to enter a notch in the other section to limit the inward movement only of the sections, substantially as described.

13. In a folding chair, the combination of 120 the front and back legs pivoted together, the 115 sectional rockers, the arms pivoted to the upper ends of the back legs, the back loosely connected to the upper ends of the front legs, and means for locking the back in an upright position, substantially as described.

14. In a folding chair, the combination with 125 the front and rear legs pivoted together, of a back having a slideable hinge connection with the upper ends of the front legs, pins t t carried by said arms, and arms u u on said front legs, adapted to be engaged by said pins, substantially as described.

15. In a folding chair, the combination with 130 pivoted folding front and back legs, of a back connected to the front legs and means for locking the back in an upright position, arms connected at one end to the back legs and

means on the front legs for limiting the movement of the arms, substantially as set forth.

16. In a folding chair, the combination of crossed front and back legs pivotally connected to each other, rounds between the parts of the legs, cross-bars also between the parts of the legs forming supports for a seat, arms connected to the back legs, another cross-bar, and means on said cross-bar for limiting the movement of the arms, substantially as described.

17. In a folding chair, the combination with pivoted folding front and back legs, of sectional rockers secured thereto, a back connected to the front legs, and means for locking the back in an upright position, arms connected at one end to the back legs, and

means on the front legs for limiting the movement of the arms, substantially as set forth.

18. In a folding chair, the combination with 20 pivoted folding front and back legs, of sectional folding rockers connected to the legs, arms connected to move with one set of legs, a back connected to the other set of legs, and means for locking the back in an upright position, substantially as described. 25

In testimony whereof I have signed my name to this specification in the presence of two subscribing witnesses.

WILLIAM T. SEERUP.
